UNITED STATES PATENT OFFICE.

RICHARD H. LUFKIN, OF CHELSEA, MASSACHUSETTS.

LEATHER-FOLDING MACHINE.

SPECIFICATION forming part of Letters Patent No. 294,894, dated March 4, 1884.

Application filed January 7, 1884. (No model.)

To all whom it may concern:

Be it known that I, RICHARD H. LUFKIN, of Chelsea, in the county of Suffolk and State of Massachusetts, have invented a new and useful Improvement in Leather-Folding Machines, which will, in connection with the accompanying drawings, be hereinafter fully described, and specifically defined in the appended claims.

10 My present invention is an improvement upon the inventions described in Letters Patent of the United States numbered 191,006 and 202,844, granted to me; and it consists in the divers devices and combinations of mechanism hereinafter more fully set forth and claimed, whereby the pressure of the fold-presser may at will, while the machine is in active operation, be relieved and restored, and conjointly therewith or independently thereof the cutting devices employed to slit the edge may also at will be rendered temporarily inoperative and restored to action by removing the cutting-block away from its vertically reciprocating and coacting blade, all for purposes hereinafter stated.

15 Figure 1 is a front side elevation of my machine embodying my present improvements. Fig. 2 is an under side view of the same. Fig. 3 is a sectional end elevation as viewed from the left of Fig. 1. Fig. 4 is an end view from the right of Fig. 1, showing the connections between the driving-wheel and the presser-lever. Fig. 5 is an enlarged detached view of one end of the rock-bar and its attachments as viewed from the right of Fig. 3, and sectioned on line *x* *x* in said figure. Fig. 6 is an enlarged detached sectional view as viewed from the right of Fig. 5, and as on line *y* *y* therein. Fig. 7 is a detached view of the work-20 plate, showing a plan thereof and of the sliding cutting-block fitted therein. Fig. 8 is a vertical section through the cutting-block, &c., taken as on line *z* *z*, Fig. 7.

25 I have discovered by the practical use of my machine for folding the edges of leather that it is sometimes desirable to be able to suspend the effective operation of the cutting devices employed for slitting the edges, and to renew the same at will while the machine is 30 in active operation; also, to be able to relieve and restore the pressure upon the folded edge

at will while the machine is in active operation. Such temporary suspension of the effective operations of the cutting and pressing devices is desirable when two pieces are seamed together, and the edge being folded crosses such seam. When the pressing operations on the fold are thus suspended, it is desirable to be able to suspend the slitting operations at the same time. I have therefore constructed 55 and arranged my improvements so as to be able thereto to effect these two results conjointly, while also providing for a separate and independent suspension of the cutting operations whenever desired, as hereinafter 60 described.

I have heretofore pivoted the presser-lever A, Fig. 1, upon fixed bearings in the sides of the bed-plate B and adjustably connected its long arm by means of a thumb-screw, C, secured by a check-nut, D, to a pitman, E, Figs. 1, 4, which at its upper end is secured to the driving-wheel by a screw-stud, G, fitted in a slot in said pitman, in which there is also secured a spiral spring, H, against the resistance of which said stud works, thereby affording a yielding pressure to the operative end of the presser-lever. The adjustment of lever A to pitman E by means of thumb-screw C serves to regulate the pressure end of lever 80 A relatively to the work-plate and the thickness of leather supported thereon, so as to produce the requisite pressure on a piece of certain uniform thickness, while the yielding connection of pitman E with the driving-wheel just referred to serves to prevent undue pressure when slight inequalities in the thickness of the stock occurs. In my present improved construction I pivot the presser-lever A in a rock-bar, I, which is mounted on 85 pivotal bearings J J, fixed in the sides of the bed-plate B, Fig. 2, and I pivot the presser-lever upon centers K K, fixed in short arms or projections on said bar and eccentric to the axis of the bar, and thereby the rocking of the 90 bar, as hereinafter described, raises and lowers the said supporting-centers of the presser-lever, and thus changes the relations of the pressure end thereof to the work upon the work-plate without interrupting the vibrations of the lever derived from the action of the driving-wheel; but when so raised by the 95 100

rock-bar I it is for the time rendered ineffect-
ive upon the folded edge, and when lowered
thereby to its normal position its effectiveness
upon the fold is restored.

- 5 To hold the lever to its effective working
position, a locking-lever, L, is pivoted to one
of the short arms or projections of the rock-
bar I. This lever has two arms at nearly right
angles to each other, one extending from its
10 pivot M downward, and the other horizontally
beneath the bed-plate, and resting firmly up
against the under side of the bed, and secured
in that position by a counteracting-spring, N,
which also has a bearing against the under
15 side of the bed-plate, on the opposite side of
the pivotal support of the rock-bar, while at
its lower end it exerts the requisite expansive
force upon a projecting seat extending from
the rock-bar, being secured upon said seat by
20 a screw projecting upward through the seat,
as clearly shown in Fig. 5. By pulling the
vertical arm of lever L up into a horizontal
position, turning it on its pivot M, the rock-
bar I will be thereby released, and both by
25 the action of the presser-lever on the work-
plate or leather and the force of spring N the
bar will be rocked into the position shown by
dotted lines in Fig. 5, and the pressure end of
lever A will be raised out of effective contact
30 with the folded edge of the leather without in-
terrupting the feeding and folding operations
of the machine or the vibrations of the lever,
as before stated, and when the rock-bar is thus
released by the operator raising lever L, as de-
35 scribed, the lever is so pulled up against the
contractile force of a spring, O, one end of
which is secured to said lever and its opposite
end to the rock-bar, as shown, and which serves
to return the lever instantly to its first pos-
40 sition when released by the operator, and to
hold it steadily in position, preventing any
noisy rattle therefrom which might otherwise
occur from the jarring of the machine in op-
eration.
- 45 The horizontal arm P of the locking-lever
is extended and provided with a hole, as
shown, through which it may be connected
with a treadle when found more convenient to
50 operate with the foot, as may sometimes be
the case. The action of the lever and springs
will be the same in that case as when operated
by the hand of the operator, and the result
the same, as is obvious.

The turning of the locking-lever L upon its
55 pivot M, as just described, operates through
the said rocking of bar I to suspend the effect-
ive operations of the pressure-lever upon the
folded edge, and the release of lever L and its
60 return by spring force, as described, restores
the pressure-lever to its effective work.

To suspend the effective operations of the
cutting devices conjointly with the suspension
of the pressure just described, I have made
the following improvements in the cutting de-
65 vices heretofore employed by me, and which
comprise a vertically-reciprocating cutter-bar;

Q, Figs. 1, 3, carrying a cutter, R, whose blade
S co-operates with the edge of a cutting-block,
T; Figs. 3, 7; S. This block T has heretofore
been only adjustable in the work-plate by 70
sliding back and forth to regulate its relation
to the blade S, and then securing it in such
fixed position by a screw, U. Now, in order
that I may be able to suspend the effective
75 cutting operations when I suspend the press-
ing, as described, or independently of the
pressing devices, if desired, I have secured
the cutting-block T to a slide, V, Fig. 8, which
slide in part projects downward through a
80 slot in the bed-plate, and to such projection I
secure an under slide, W, which works in a
recess in the under side of the bed-plate, as
shown. From this under slide there projects
downward a stud, y, which passes through a
85 slot in a lever, a, Figs. 2, 3, pivoted to the
under side of the bed at b, and the opposite
end of which is jointed to a rod, c, which ex-
tends horizontally along the under side of the
bed and passes out through the edge thereof
90 at the front side of the machine, and is pro-
vided with a cap or knob, d, by which it may
be operated. There is also a shoulder, e,
formed upon said rod, which rests against a
pin, f, that projects from and moves with le-
ver L, so that when lever L is operated, as 95
hereinbefore described, said pin f will act
against shoulder e, and thereby force said rod
c inward, which movement will rock lever a
upon its pivot b, and thus, through the slides
connected with its slotted end by stud y, will 100
impart movement to the cutting-block T away
from its coacting blade S, thereby suspend-
ing the effective cutting operations conjointly
with the suspension of the pressing operations.
105

A spring, h, Fig. 2, having one end resting
against a stop, i, on the under side of the bed-
plate, and its opposite end bearing against
the lever a, counteracts the last-described
movement of said lever, and as soon as the le-
ver L is released and allowed to return, as de-
scribed, to its operative position against the
bed and rock-bar, spring h, by its expansive
force, immediately returns the parts connect-
ed with lever a to their first position, carry-
ing the cutting-block into coaction with blade 115
S, and thus instantly restoring the effective
cutting operations. When it is desired to thus
suspend the cutting operation without inter-
rupting the action of the pressing devices, it
may be done by simply pressing inward on 120
knob d, which is free to move in that direc-
tion, carrying shoulder e away from pin f, and
by such movement will produce precisely the
same effect as if moved by pin f, as just de-
scribed, as must be obvious without further 125
explanation.

Having thus fully described the object, con-
struction, mode of operation, and effect of my
improvements, I claim as my invention—

1. In a leather-folding machine, the combi- 130
nation of a fold-presser and means, substan-
tially as described, whereby the effective op-

eration of such presser may, at will, be suspended and restored while the machine is in operation, as and for the purposes set forth.

2. In a leather-folding machine, a pressure-lever, A, mounted upon movable centers, combined with means for moving its pivotal centers, and means, substantially as described, for vibrating such lever, substantially as and for the purposes specified.

10 3. The combination of rock-bar I, pivoted to the bed-plate, fold-presser A, pivoted to the rock-bar, locking-lever L, also pivoted to said rock-bar, and arranged to secure the bar in position, and counteracting-spring N, all substantially as and for the purposes specified.

4. In a leather-folding machine, a cutting mechanism composed of a fixed cutting-block and a coacting reciprocating cutter, combined with means, substantially as described, whereby the effective operation of the cutting devices may at will be suspended and restored by a separation of the block from the reciprocating cutter while the machine is in active operation, substantially as and for the purposes specified.

25 5. In a leather-folding machine employing

pressing and cutting devices, substantially as described, the combination therewith of means, substantially as described, whereby the effective operations of such cutting and pressing devices may be conjointly suspended and restored, as and for the purposes specified.

6. The reciprocating cutter S, cutting-block T, arranged to slide as described, lever a, pivoted to the bed and connected with said block, 30 rod e, jointed to said lever and supported in a horizontal position by the bed, and the counteracting-spring h, combined and arranged to operate together substantially as and for the purposes specified.

40 7. The combination of the pressing devices, comprising rock-bar I, fold-presser A, lever L, and spring N, the cutting devices comprising the cutter S, cutting-block T, lever a, rod e, and spring h, and means whereby said cutting and pressing devices are connected and conjointly operated, as and for the purposes specified.
